UNITED STATES PATENT OFFICE.

HARRY S. LEE, OF PLYMOUTH, MICHIGAN.

PERMANENT MOLD CONSTRUCTION.

Application filed February 13, 1925. Serial No. 8,863.

This invention relates to permanent mold construction and has for its object the means for varying the size of the mold cavity for casting any desired size of casting with the same mold. The specific mold here illustrated shows molds for casting window weights but obviously this same principle of varying the size of the mold cavity could be applied to the molds for casting different articles.

Another object of the invention is the provision of means for casting a hole through the casting by using a core which may be automatically retracted so as to permit the casting to be discharged from the mold.

In the drawings:

Fig. 1 is an elevation of a mold.

Fig. 2 is an elevation of the mold showing the opposite side from that shown in Fig. 1.

20 Fig. 3 is a section taken on the line 3—3 of Fig. 1, showing the retractable cores.

Fig. 4 is a section on the line 4—4 of Fig. 2, showing the adjustable inserts for varying the size of the mold cavity.

25 In the illustration, I have illustrated only half of the mold, but of course it is understood that to complete the mold there is another half identical with the one illustrated which is adapted to mate with this mold half and is constructed in exactly the same way and contains the same adjustable inserts and retractable cores which are actuated and secured to the mold in the same manner.

30 The mold half illustrated comprises preferably a gray iron casting designated *a*. It is provided with one or more molding cavities *b*, which are here shown as elongated cavities for casting the ordinary window weight, with which we are all familiar.

35 The walls of the cavity are provided with a plurality of tapped holes *c* and the inserts *d* are arranged to fit within the mold cavity and the bolt or set screw *e* is screwed into the tapped hole and into the insert for securing the same in place. As shown in Figs. 2 and

40 45 this insert is shown secured in the molding cavity and materially shortens the length of the same so that when the casting is poured a shorter window weight may be formed than would be formed if the inserts were left out. The tapped hole *c* when not in use may be plugged up with the short studs *f* so as to prevent the molten metal from leaking out.

50 55 The size of the mold cavity can be varied by securing the inserts in any one of a plu-

rality of positions by passing the set screw or bolt *e* through any one of the tapped holes *c*. The size of the molding cavity could also be varied by removing the insert and securing a larger or smaller insert in its place. This is shown by the dotted lines *g*, which show an insert which is of much greater length than the one that is illustrated by the solid lines. Obviously both of these methods could be employed whenever desired.

In casting a window weight, it is necessary to cast a hole through the same, but obviously a core must be provided which may be easily retracted or knocked out so as to permit the casting to be discharged from the mold. It is the usual practice to make a sand core which may be knocked out of the casting after the same has been discharged, but these sand cores entail a great deal of 70 labor in making the same and necessitates the placing of a new core at every casting operation.

To overcome this difficulty, I provide the retractable core *h* which is supported in the recess *i* in the mold. This core or pin *h* is provided with a reduced portion *j* which is projected out of the back of the mold, the reduced portion forming a shoulder *k* which is arranged to abut the bottom of the recess *i* so as to limit the retracting movement of the core. The drawings illustrate a pair of mold cavities, but obviously one mold could be used in a mold but it is more practical to cast a pair of window weights simultaneously. Because of this I show a pair of cores *h* which are bridged at their free ends by a connecting bracket *m*. This bracket *m* is secured by means of the pins *n* to the reduced portion of said cores, and supports a roller *o* which is arranged to engage a cam *p* as shown in Fig. 3, so that as the mold moves by the cam the cam presses the cores inwardly the desired distance until the cores carried by one mold half abut the cores carried by the other half. Springs *r* surround the reduced end portion of the core and exert an outward pressure on the same for holding the core in a retracted position, forcing the shoulder *k* up against the bottom of the recess *i*. As the roller *o* rides off the cam it allows the cores to be forced outwardly under the spring power and to be retracted within the recess, whereupon the mold halves may be separated automatically 100 or by hand, thus permitting the casting to be discharged from the mold.

When using permanent molds such as illustrated in the drawings, in a permanent mold machine, it is obviously an advantage to have cores which may be automatically retracted and projected from and into the molding cavity at the proper time so as to eliminate as much as possible of the human element. This provides more uniform castings and also eliminates considerable of the 10 labor costs in large production.

What I claim is:

1. In a mold for casting metals, the combination of a mold having a permanent molding cavity adapted to receive molten 15 metal and impart a finished contour thereto, an insert adapted to be positioned in said molding cavity, and means for removably securing the insert to the normal molding cavity at various points to vary the size of 20 said cavity.
2. In a mold for casting metals, the combination of a mold having a normal molding cavity adapted to impart a finished contour to the article cast, an insert shaped to fit 25 within said finished cavity, and means for removably securing said insert at various

points in said cavity to vary the size of said molding cavity to replace part of the normal finished contour of said molding cavity.

3. In a mold for casting metals, the combination of a mold having a normal molding cavity adapted to impart a finished contour to the article cast, and a removable insert secured in said molding cavity at various points for adjustably reducing the size thereof and to permit the increasing or decreasing of the size of said molding cavity by securing smaller, or larger, inserts therein.

4. A mold for casting metals, comprising in combination a permanent molding cavity 40 adapted to impart a finished contour to the article cast therein, means insertable within said permanent cavity to reduce the size thereof and to form a temporary molding cavity of different size or shape, and retractable means for forming an impression in the casting independently of the use of said normal cavity or temporary cavity.

In testimony whereof I have affixed my signature.

HARRY S. LEE.
